COIL-FORMING APPARATUS

Oscar F. Arthur, Belle Vernon, Pa.

Application October 13, 1942, Serial No. 461,873

8 Claims. (Cl. 153—67)

My invention relates to coil-forming apparatus and more particularly to the forming of helical coils of heavy wire such as those shown in the drawing of my application Serial No. 437,989, filed April 7, 1942 (now Patent No. 2,315,180), for hingedly connecting the panels of wire mat structures. It will of course be understood that these coils can have various other uses.

One object of my invention is to provide a coiling apparatus of simple form and a minimum number of moving parts.

Another object of my invention is to provide apparatus for bending wire or the like to helical form, and wherein the pitch or angle of the helical turns can readily be varied.

One form which my invention may take is shown in the accompanying drawings wherein Figure 1 is a perspective view of the apparatus; Fig. 2 is a longitudinal sectional view of a portion of the apparatus of Fig. 1, on an enlarged scale; Fig. 3 is an enlarged plan view of the rear portion of the structure of Fig. 1, and Fig. 4 is an enlarged plan view of a forward portion of the apparatus of Fig. 1.

The mechanism is shown as mounted upon a framework having upright members 4 and 5, with cross bracing at 6, 9, 10, 11 and 12. Tensioning or truss rods 13 are connected at their outermost ends to the members 8 and 12 and are joined together by a turn buckle 14, to brace the structure in a manner common to framework of this character.

A mandrel 17 is journaled in bearings to be hereinafter described and at its front end is driven by an electric motor 18 through a pulley 19 that is secured to the mandrel. At its front end the mandrel 17 is supported in a close fitting bearing on the framework 20, while at its rear end it extends loosely through a hole in the cross-piece 12, which hole is sufficiently large to permit the wire coil to be pushed therethrough. Intermediate its ends the mandrel is supported by bearings 22 and 23 that are carried on a wheeled truck that has a roller 24 at each of its four corners, these rollers riding on trackways 25 that are carried by the framework. The bearing 23 is large enough to accommodate the coil also. The axles of the truck are connected by reach rods 26 and 27. The rod 27 is extended at 28 to engage a roller 30 on a push rod which controls a switch 31, for the purpose of automatically interrupting the motor circuit when the truck reaches the front end of the machine.

A wheeled carriage 32 which carries bending dies or elements, has its wheels 33 riding upon

the tracks 25. The carriage has depending flanges 36 extending downwardly from the bed plate 37 of the carriage, at the inner sides of the rails 25, to serve as guides during travel of the carriage.

At its forward end the carriage has a tubular bearing 40 that has close sliding fit with the mandrel 17 and is provided with an oil cup 41 from which drops of oil fall upon the mandrel 10 to lubricate it, the flow of oil being controlled by a valve which is operated by a handle 42. The carriage is also provided with an arm 43 that has guide rollers 44 thereon for a stock of wire 45 that is drawn from a coil (not shown) 15 that may be located on the floor or elsewhere, or a wire-supply coil can be carried on a support 38 that is mounted on hangers 38a. A pair of bending rolls 46 and 47 are secured to the arm and serve as a wire-guiding element, while a 20 pair of rollers 48 and 49 that serve as second and third wire-guiding elements, respectively, are mounted on the carriage in position to engage the turns of wire as it is wrapped on the mandrel. These rolls not only assist in placing permanent 25 bends or turns of desired pitch in the wire, but serve as a means for feeding the carriage forwardly as the wire is wound thereon through rotation of the mandrel. The mandrel is held against turning relative to the wire spiral by a 30 clamp 51. As the mandrel rotates, the wire 45 will be drawn past the bending dies or rollers 46—47 and wrapped around the mandrel. The turns of the wire helix will engage at their forward sides against the rear sides of the rollers 35 48—49, successively, whose axes are set angularly relative to one another and to the axis of the mandrel. The roller 49 is shown as positioned rearwardly of the roller 48, a distance of about one-half of the helical pitch. As the wire 40 is of heavy gage, such as 10 gage, for example, and may be of low carbon steel, so that it retains its bent shape and has considerable stiffness, the screw-like action of the wire turns on the rollers 48—49 will force the carriage 32 forwardly along the mandrel 17, during rotation of the mandrel.

The position of the rollers 48 and 49 relative to the roller 46, determines the pitch of the helix formed on the mandrel. Thus, if they are 45 set closer to the roller 46, the pitch will be shorter and the turns closer together than if they are set farther back on the carriage. To permit of such adjustments, the rollers are journaled on slide plates 53 and 53a respectively that are 50 slotted for the reception of clamping screws 54

and 54a respectively that have threaded engagement with the plate 37 of the carriage. At its rear end each slide plate has a down-turned flange 55 that carries an adjusting screw 56 which has thrust engagement with a sleeve 57 that surrounds a shaft 58 which carries the rear rollers 33. Upon loosening the screws 54 and 54a, the screws 56 can be turned to shift the plates 53 and 53a longitudinally of the carriage. With changes in pitch, the rollers 48 and 49 will have to be adjusted relative to one another, by their adjusting screws, in accordance with such changes.

In further explanation of the operation of the apparatus, at the beginning of a coil-forming operation, the carriage 32 is moved to the rear of the machine, at the uprights 5, the truck 24-26 being pushed rearwardly against the uprights 5, by the rear end of the carriage. The wire 45 is then threaded past the rollers 44-46, 47, 48 and 49, and a few turns thereof made around the mandrel and pushed through the cross bar 12. Thereupon the clamp 51 is applied to secure the rear end of the wire to the mandrel. A starter switch 59 is then closed to set the motor 18 in operation to rotate the mandrel 17. As above explained, this rotation will result in wrapping the wire around the mandrel in helical turns with a pitch depending upon the adjustment of the rollers 48-49 relative to the roller 46.

After the carriage 32 has advanced some distance, its front end will engage the front end of the truck 24-26 and push such truck forwardly. The purpose of the truck is to carry the bearings 22 and 23 which support the mandrel 17 at points between its ends and the carriage, so as to avoid whipping or excessive vibration of the mandrel, which is necessarily of considerable length—12 ft. to 15 ft. or more.

When the truck and the carriage have approached their foremost limit of movement, the bar 23 will actuate the switch-operating element 39, to interrupt the motor circuit. The mandrel at this time is approximately filled with a coil. Thereupon the clamp 51 is removed and the carriage 32 pulled backward manually to its starting position at the rear end of the machine. This rearward movement of the carriage is effected by a winch 60 and a cable 61 that is connected to the carriage, the winch being operated in the usual manner to wind the cable thereon. During this backward movement, the wound helices will slide off the rear end of the mandrel and unbent portions of the wire 45 will be carried rearwardly along with the guide arm 43. There will still be a few turns of wire remaining on the rear end of the mandrel, and a cut will be made at the end of the mandrel to sever the rearwardly-projecting portion of the helix from that which remains on the mandrel. Thereupon the clamp 51 is again applied to the wire and the mandrel as shown in Figs. 1 and 3 and the starter switch 59 operated to perform another coiling operation.

I claim as my invention:

1. Coiling apparatus comprising a trackway, a mandrel extending parallel to the trackway, means for rotating the mandrel, a carriage movable along the trackway, means for clamping an end of a wire on the mandrel, at a point rearwardly of the carriage, a wire-guiding element movable with the carriage and positioned to direct the wire in a lateral direction to the mandrel, and a second wire-guiding element on the

carriage at a point rearwardly of the first-named element and positioned to engage the forward sides of the wire turns which are formed on the mandrel as the wire is drawn past the first-named element during rotation of the mandrel, the second-named guiding element being adjustable relative to the first-named element, in a direction longitudinally of the carriage, to vary the pitch of the wire turns on the mandrel.

2. Coiling apparatus comprising a trackway, a mandrel extending parallel to the trackway, means for rotating the mandrel, a carriage movable along the trackway, means for clamping an end of a wire on the mandrel, at a point rearwardly of the carriage, a wire-guiding element movable with the carriage and positioned to direct the wire in a lateral direction to the mandrel, a second wire-guiding element on the carriage at a point rearwardly of the first-named element and positioned to engage the forward sides of the wire turns which are formed on the mandrel as the wire is drawn past the first-named element during rotation of the mandrel, and a third element on the carriage, at a point rearwardly of the second-named element, and positioned to engage the forward sides of the wire turns as it is being wrapped on the mandrel, to exert a thrust that will move the carriage forwardly during the wrapping of wire on the mandrel.

3. Coiling apparatus comprising a trackway, a mandrel extending parallel to the trackway, means for rotating the mandrel, a carriage movable along the trackway, means for clamping an end of a wire on the mandrel, at a point rearwardly of the carriage, a wire-guiding element positioned adjacent to a forward portion of the carriage and movable therewith to direct the wire in a lateral direction to the mandrel, a second wire-guiding element on the carriage at a point rearwardly of the first-named element and positioned to engage the forward sides of the wire turns which are formed on the mandrel as the wire is drawn past the first-named element during rotation of the mandrel, a mandrel bearing movable on the trackway and having movement axially relative to the carriage, so arranged that in one direction of carriage travel the bearing will be brought into proximity to the adjacent end of the carriage during its final stage of movement in that direction, and means operative upon movement of the carriage in the opposite direction to shift the bearing axially therewith only after the carriage has travelled a substantial distance.

4. Coiling apparatus comprising a trackway, a mandrel extending parallel to the trackway, means for rotating the mandrel, a carriage movable along the trackway, means for clamping an end of a wire on the mandrel, at a point rearwardly of the carriage, a wire-guiding element positioned adjacent to a forward portion of the carriage and movable therewith to direct the wire in a lateral direction to the mandrel, means for moving the carriage forwardly at a predetermined rate during rotation of the mandrel to coil a wire thereon, and a bearing for the mandrel having movement axially relative to the carriage and movable along the said trackway, the connection being such that in one direction of travel the bearing will lag a substantial distance behind the carriage.

5. Coiling apparatus comprising a trackway, a mandrel extending parallel to the trackway, means for rotating the mandrel, a carriage mov-

able along the trackway, means for clamping an end of a wire on the mandrel, at a point rearwardly of the carriage, a wire-guiding element positioned adjacent to a forward portion of the carriage and movable therewith to direct the wire in a lateral direction to the mandrel, means for moving the carriage forwardly at a predetermined rate during rotation of the mandrel to coil a wire thereon, and bearings for the mandrel, located forwardly and rearwardly of the carriage and movable along the trackway, the bearings having movement axially relative to the carriage, so arranged that in one direction of travel by the carriage one bearing will lag behind the same, and in the other direction the other bearing will lag behind the carriage.

6. The method of forming helical coils from wire which will retain a bent shape and is of substantial stiffness, which comprises drawing the wire past a guide and securing one end thereof to an end of a mandrel, imparting relative rotative movement to the guide and the mandrel about the longitudinal axis of the mandrel, and simultaneously imparting relative movement to the mandrel and the guide in a direction longitudinally of the mandrel axis, toward the other end of the mandrel, the turns of the helices being utilized to impart the said relative longitudinal movement.

7. Coiling apparatus comprising a mandrel and

means for rotating it, a carriage movable forwardly along the mandrel, a wire-guiding element movable with the carriage and positioned to direct wire to the mandrel, in a path angular to the axis of the mandrel, means for connecting the foremost end of a wire to the mandrel, and an element on the carriage in position to engage the forward sides of the wire turns which are formed on the mandrel during its rotation, whereby the table and said elements are progressively advanced during the forming of a coil on the mandrel.

8. Coiling apparatus comprising a mandrel and means for rotating it, a carriage movable forwardly along the mandrel, a wire-guiding element movable with the carriage and positioned to direct wire to the mandrel, in a path angular to the axis of the mandrel, means for connecting the foremost end of a wire to the mandrel, and an element on the carriage in position to engage the forward sides of the wire turns which are formed on the mandrel during its rotation, whereby the table and said elements are progressively advanced during the forming of a coil on the mandrel, the table being movable also rearwardly along the mandrel, when the said wire end is disconnected from the mandrel, whereby the second-named element will strip the coil from the mandrel.

OSCAR F. ARTHUR.
